ABSTRACT

[21] Appl. No.: 09/163,000

There is provided a globe supporting structure that supports a globe of a gas lantern which burns combustible gas discharged from a gas cartridge containing the combustible gas by means of a burner head located inside the globe, including a ventilator positioned above the globe, a plurality of wires rotatably arranged on the ventilator, each of which rotates about the ventilator, and is shaped so as to be capable of reaching a bottom surface of the globe, and a globe supporting plate that supports the globe, and is provided with first arrangement which is detachably engagable with a portion of the wires reaching the bottom surface of the globe. In accordance with the globe supporting structure, the globe can be removed easily from the globe supporting plate without breaking the globe. In addition, unlike a conventional gas lantern known in the art, the double operation of first removing the globe from the globe supporting plate and then removing the ventilator from the globe, is not required, and the globe can be removed by only one operation of releasing the engagement between the wires and the first arrangement.

FIG. 1
PRIOR ART

FIG.2

FIG.3

FIG.4

FIG.5

FIG.6

FIG.7

FIG.8

STRUCTURE FOR SUPPORTING A GLOBE USED FOR A PORTABLE GAS LANTERN

BACKGROUND OF THE INVENTION

1. Field of the Invention

The present invention relates to a so-called outdoor, portable gas lantern, and more particularly, to a structure for supporting a globe which is one of structural components of a portable gas lantern.

2. Description of the Related Art

FIG. 1 shows an example of a conventional portable gas lantern known in the prior art. In FIG. 1, a portable gas lantern **10** is comprised of a gas cartridge **11** containing compressed combustible gas and a gas burner **12** that can freely be attached to and detached from the gas cartridge **11**. The gas cartridge **11** and the gas burner **12** are assembled in a hermetically sealed state by a gasket **13**.

The gas burner **12** is connected to the gas cartridge **11**, and the connection is comprised of a plug fitting **14** through which combustible gas supplied from the gas cartridge **11** passes, a knob **15** connected to a gas flow adjusting spindle that adjusts the flow rate of the combustible gas passing through the plug fitting **14** by controlling the degree of opening of a gas passage formed in the plug fitting **14**, a burner head **16** with a number of openings **16a** penetrating the surface of the head, a mixing tube **17** connecting the plug fitting **14** to the burner head **16**, an ignition electrode **18** for igniting a gas mixture of air and the combustible gas flowing in the mixing tube **17**, and an ignition button **19** installed on the plug fitting **14** for actuating the ignition electrode **18**.

In addition, an approximately hemispherical globe supporter **20** is mounted on the mixing tube **17**, for installing a globe, and a globe **21** that is shaped substantially as a cylinder is engaged with the globe supporter **20**. The globe **21** is open at both the upper and lower ends, and is composed of a transparent material such as transparent glass or frosted glass. A ventilator **22** is mounted at the top of the globe **21**, so that the ventilator covers the top of the opening of the globe **21**.

This portable gas lantern **10** is operated as follows.

First, a substantially spherical light emitting body (not illustrated) called a mantle is installed to cover the burner head **16**, before the gas lantern **10** is used.

A combustible gas in a pressurized state enters into the plug fitting **14** from the gas cartridge **11**, and is fed into the mixing tube **17** while the knob **15** connected to the gas flow adjusting spindle controls the gas flow. The mixing tube **17** is provided with an opening **17a** through which external air is taken into the mixing tube **17** by a negative pressure produced when the combustible gas passes through the interior of the mixing tube **17**. The combustible gas is mixed with air entering through the opening **17a**, to produce a gas mixture of the combustible gas and air.

When the user of the lantern presses the ignition button **19** after the gas mixture enters the burner head **16**, a spark discharge occurs between the ignition electrode **18** charged positively and the mixing tube **17** charged negatively, and the spark ignites the gas mixture flowing in the mixing tube **17** through the opening **17a**. In this way, the ignited gas mixture flows out through a number of openings **16a** formed in the surface of the burner head **16**, so as to illuminate the mantle installed around the burner head **16**.

As described above, the light emitting body (mantle) is illuminated by the burning combustible gas, and the gas lantern **10** can be used as a light source outdoors, for instance.

As shown in FIG. 1, the globe **21** is mounted on the globe supporter **20** by a pair of globe mounting springs **23**, and the globe **21** can be freely attached to and removed from the globe supporter.

5 The globe mounting springs **23** are comprised of leaf springs shaped in a crank, and one end **23a** is fixed to the inner wall of the globe supporter **20**. The other end **23b** is structured as a free end, and the globe **21** is supported by the globe supporter **20** because the free end **23b** presses the inner wall of the globe **21** in an outward direction. The crank portion **23c** of the globe mounting spring **23** is located outside the globe supporter **20**. When the upper and lower surfaces of the crank portion **23c** are pressed together, the free end **23b** of the globe mounting spring **23** rotates around 10 the crank portion **23c**, and engagement between the free end **23b** and the inner wall of the globe **21** is released, and as a result, the globe **21** can be removed from the globe supporter **20**.

20 A number of arc-shaped springs **24** are provided at the bottom of the ventilator **22**. The springs **24** extend outwards from the ventilator **22**, enter the interior of the globe **21** through the top surface of the opening of the globe **21**, and engage with the inner wall of the globe **21**. Thus arranged, the ventilator **22** is supported by the globe **21**.

25 As described above, the globe **21** is supported by the globe supporter **20** as the globe mounting springs **23** press on the inner wall of the globe **21**. When the globe **21** is to be removed from the globe supporter **20**, the globe mounting springs **23** do not interfere with the removal of the globe **21** 30 because the crank portions **23c** have been pressed and the springs have been rotated inwards from the globe **21**, so the springs do not obstruct the removal of the globe **21**.

35 When the globe **21** is reinstalled onto the globe supporter **20** after being once removed, the upper and lower surfaces of the crank portion **23c** is pressed from both upper and lower surfaces, and while the globe mounting springs **23** are rotated inwards relative to the globe **21**, the globe **21** is 40 mounted on the globe supporter **20**, and thereafter pressure on the crank portion **23c** is released, so that the free ends **23b** of the globe mounting springs **23** contact the inner wall of the globe **21**.

45 At this time, if the pressure on the crank portion **23c** is released instantaneously, the free ends **23b** of the globe mounting springs **23** are acted upon by the whole spring force which was accumulated by the rotation of the globe mounting springs **23**, therefore the inner wall of the globe **21** is instantaneously impacted by the free ends **23b** of the globe mounting springs **23** with an extremely large force. 50 Unfortunately, the globe **21** has been manufactured with a thin wall to give a high transmission of light. As a consequence of these factors, the globe **21** has often been cracked by the globe mounting springs **23** when the globe **21** was mounted on the globe supporter **20**.

55 Therefore, when a consumable component, the mantle, is to be replaced in a conventional gas lantern **10** known in the prior art, the mantle cannot be replaced unless the globe **21** is removed, so there is the inconvenience of preparing a spare globe **21** at any time to cope with the breakage of the globe **21**.

60 In addition, the ventilator **22** is also installed at the opening of the globe **21** by the springs **24** pressing on the inner wall of the top of the globe **21**. Therefore, also when the ventilator **22** was removed from the globe **21**, the same problem as above used to occur. In other words, because the ventilator **22** engages with the globe **21** with a large spring force, the globe **21** with a thin wall often cracks if an attempt

is made to withdraw the ventilator 22 from the globe 21 with excessive force.

Furthermore, with the conventional gas lantern 10 shown in FIG. 1 as known in the art, the ventilator 22 and the globe supporter 20 are separately attached to the globe 21, so even if an attempt is made to remove the globe 21 only to clean off soot adhering to the inner wall of the globe 21, two removal operations must be performed; removal of the ventilator 22 from the globe 21, and removal of the globe 21 from the globe supporter 20.

SUMMARY OF THE INVENTION

In view of the above-mentioned problems associated with a conventional gas lantern known in the art, it is an object of the present invention to provide a gas lantern from which the globe can be removed easily without breaking the globe and the globe can be removed with only one operation.

There is provided a globe supporting structure that supports a globe of a gas lantern which burns combustible gas discharged from a gas cartridge containing the combustible gas by means of a burner head located inside the globe, including a ventilator positioned above the globe, a plurality of wires rotatably arranged on the ventilator, each of which rotates about the ventilator, and is shaped so as to be capable of reaching a bottom surface of the globe, and a globe supporting plate that supports the globe, and is provided with first means which is detachably engagable with a portion of the wires reaching the bottom surface of the globe.

In accordance with the above-mentioned globe supporting structure of a gas lantern, a plurality of wires (for example, two wires) are installed in a freely rotatable manner on a ventilator installed above the globe. When these wires are rotated about the ventilator, the wires reach a bottom surface of the globe supporting plate that supports the globe, and engage with the first means formed on the bottom surface of the globe supporting plate. In this state, the wires contact the globe along the outer surface of the globe between the ventilator and the globe supporting plate, and support the globe at its outer periphery.

In the globe supporting structure of a gas lantern, the wires engage only with the first means provided on the globe supporting plate, and the wires do not press against the globe. The wires merely contact the globe. Therefore, unlike the conventional gas lantern 10 shown in FIG. 1, the globe will not be broken at any rate when the wires are attached or removed.

On the contrary, when the wires are engaged with the first means, the wires surround the globe. Consequently, the wires act as a guard for the globe, and even when the gas lantern rolls over, the wires will hit the ground first, so that the globe can be protected from breakage.

The wires can detachably engage with the first means. Therefore, by engaging the wires with the first means, the globe can be fixed on the globe supporting plate, and when engagement between the wires and the first means is released, the globe can be removed from the globe supporting plate. In other words, either when the globe is to be mounted on the globe supporting plate or when the globe is to be removed from the plate, the user can achieve the purpose with only one operation, that is, by engaging or disengaging the wires with or from the first means, for engaging or removing the globe with or from the globe supporting plate, respectively. According to the present invention, the two removal operations required with the conventional gas lantern 10 shown in FIG. 1, that is, when

the globe 21 is to be removed, the ventilator 22 is removed from the globe 21, and then the globe 21 is removed from the globe supporter 20, are no longer needed.

The first means constructed on the globe supporting plate can be structured in various ways.

For example, the first means may be provided with a protruding portion that protrudes downward, and can rotate in a vertical direction.

According to this type of the first means, the wires engage with the first means with the wires over-riding the protruding portion. Once the wires have over-ridden the protruding portion, the wires can no longer over-ride the protruding portion in the reverse direction, so the wires are fixed in place. That is, the globe is fixed to the globe supporting plate, together with the ventilator.

To disengage the wires from the first means, the protruding portion must just be pushed upwards. By pushing the protruding portion upwards, a height of the protrusion becomes relatively small, and the wires can easily override the protruding portion. Therefore, the wires are disengaged from the first means. Hence, both the globe and the ventilator are ready to be removed from the globe supporting plate.

If the first means is composed of a resilient material, the protruding portion once pushed upward can be reset in place by its own spring force, so the effectiveness of the first means increases.

Although the first means having the aforementioned protruding portion can be formed as a separate part, and mounted on the globe supporting plate, it is also possible to construct the first means as a part integrated with the globe supporting plate. More explicitly, the first means can be formed as a part of the globe supporting plate by cutting away a peripheral portion of the plate. This method can contribute to simplifying the entire structure of a gas lantern because the number of components of the gas lantern can be reduced.

As the first means, the aforementioned protruding portion can be replaced with at least one projection formed on a lower surface of the globe supporting plate. This projection can be constructed in, for example, the form of a small hemisphere.

Once the wires go over the projection, it is not possible for the wires to override the projection in the reverse direction, so both the globe and the ventilator can be fixed to the globe supporting plate by locating the wires inside the projection.

Moreover, it is also possible to make the wires easily override the projection simply by slightly lifting the wires, therefore engagement between the wires and the projection as the first means can also be easily released.

The first means can be constructed as a recess formed in a lower surface of the globe supporting plate. By engaging the wires in this recessed portion, it is possible to produce the same state as the state in which the wires are fixed after overriding the aforementioned protruding portion or projection.

In the above examples, all the wires are arranged so that the wires can be removed from the globe supporting plate. When two wires are used, for example, it is possible to fix one of the wires to the rear surface of the globe supporting plate. In this case, the wire is installed on a lower surface of the globe supporting plate so that the wire can rotate with respect to the globe supporting plate. The other wire of the two is made to be capable of engaging with any of the first means for wire engagement described above.

Thus, the globe can be mounted on the globe supporting plate by engaging only the other wire with the first means for wire engagement, or the globe can be removed from the globe supporting plate by releasing the engagement between the wire and the first means for wire engagement.

In this structure, only one pair of wires and the first means must be disengaged for removing the globe, so the globe can be removed efficiently from the globe supporting plate. In addition, the ventilator is always permanently attached to the globe supporting plate, so that the ventilator is prevented from being lost after being removed from the globe supporting plate.

Any number of wires and associated first means can be incorporated. For instance, a wire and first means can be provided at each of the diagonally opposed sides of the ventilator, or four wires and four first means for wire engagement can also be arranged in a cross shape.

An advantage of the globe supporting structure of a gas lantern according to the present invention as described above, is that the globe can be removed easily from the globe supporting plate without breaking the globe. In addition, unlike a conventional gas lantern known in the art, the double operation of first removing the globe from the globe supporting plate and then removing the ventilator from the globe, is not required, and the globe can be removed by only one operation of releasing the engagement between the wires and the first means.

The above and other objects and advantageous features of the present invention will be made apparent from the following description made with reference to the accompanying drawings, in which like reference characters designate the same or similar parts throughout the drawing.

BRIEF DESCRIPTION OF THE DRAWINGS

FIG. 1 is a perspective view of a conventional gas lantern.

FIG. 2 is a perspective view of a gas lantern in accordance with the first embodiment in which the structure for supporting a globe in accordance with the present invention is employed.

FIG. 3 is an exploded view of the structure for supporting a globe, illustrated in FIG. 2.

FIG. 4 is a cross-sectional view of the first means.

FIG. 5 is a bottom view of a globe supporting plate used in a gas lantern in accordance with the second embodiment in which the structure for supporting a globe in accordance with the present invention is employed.

FIG. 6 is a bottom view of a globe supporting plate used in a gas lantern in accordance with the third embodiment in which the structure for supporting a globe in accordance with the present invention is employed.

FIG. 7 is a bottom view of a globe supporting plate used in a gas lantern in accordance with the fourth embodiment in which the structure for supporting a globe in accordance with the present invention is employed.

FIG. 8 is a bottom view of a globe supporting plate used in a gas lantern in accordance with the fifth embodiment in which the structure for supporting a globe in accordance with the present invention is employed.

DESCRIPTION OF THE PREFERRED EMBODIMENTS

FIG. 2 shows an example of the portable gas lantern 30 using an embodiment of the globe supporting structure according to the present invention.

The portable gas lantern 30 in this embodiment is comprised of a gas cartridge 31 filled with compressed combustible gas and a gas burner 32 mounted on this gas cartridge 31 in a freely detachable manner. The gas cartridge 31 and the gas burner 32 are connected in a hermetically sealed state, by a gasket 33.

The gas burner 32 is connected to the gas cartridge 31, and the connection is comprised of a plug fitting 34 through which combustible gas supplied from the gas cartridge 31 passes, a knob 35 connected to a gas flow adjusting spindle which is formed inside the plug fitting 34 and adjusts the velocity of the combustible gas passing through the plug fitting 34 by adjusting the degree of opening of a gas passage formed inside the plug fitting 34, a burner head 36 with a number of openings 36a penetrating its surface, a mixing tube 37 that connects the plug fitting 34 with the burner head 36, an ignition electrode 38 that ignites a gas mixture of air and the combustible gas, flowing in the mixing tube 37, by means of spark, and an ignition button 39 that is installed on the plug fitting 34, and actuates the ignition electrode 38.

When the gas lantern 30 is used, a substantially spherical mantle (light emitter) 40 is installed around the burner head 36.

The knob 35 is provided on the small shaft 34a protruding from the end of the plug fitting 34, and is allowed to rotate freely in the direction of the arrow A. In addition, inside the small shaft 34a, a spring (not illustrated) is installed, and even when the knob 35 is rotated in the direction of the arrow A, the knob 35 can be returned to a position parallel to the axis of the small shaft 34a.

As detailed later, the mixing tube 37 is provided with a globe supporting plate 41 installed at a predetermined height, and a globe 44 is mounted on the globe supporting plate 41. The globe 44 is fixed on the globe supporting plate 41 by wires extending from the ventilator 45.

This portable gas lantern 30 functions in the same way as the conventional gas lantern 10 known in the prior art as shown in FIG. 1.

A flow of combustible gas entering the plug fitting 34 from the gas cartridge is adjusted by the knob 35 connected to the gas flow adjusting spindle, and when the gas flow is duly adjusted, the gas enters the mixing tube 37, and is mixed with air entering through an opening 37a in the mixing tube 37 provided beneath the globe supporting plate 41, to produce a gas mixture.

After the gas mixture enters the interior of the burner head 36, the ignition button 39 is pressed. Then a spark is produced between the ignition electrode 38 and the mixing tube 37, and the spark ignites the gas mixture flowing inside the mixing tube 37. In this way, the ignited gas mixture flows out of the plural openings formed in the surface of the burner head 36, and illuminates the mantle 40 installed around the burner head 36. Thus, the present gas lantern 30 can be used, for example, as a light source outdoors by illuminating the mantle 40.

FIG. 3 is a disassembled view of the globe supporting plate 41, globe 44 and ventilator 45 that are components of the gas lantern 30 shown in FIG. 2. In FIG. 3, the globe supporting plate 41 installed at a predetermined height on the mixing tube 37 is comprised of a circular plate, at the center of which there is a circular hole, and the mixing tube 37 is inserted in this hole. A vertical lip 41a is formed around the globe supporting plate 41.

The globe supporting plate 41 is provided with four openings 41b equally spaced around the circular hole at the center, and a wire engagement member 42 is formed as the

first means for wire engagement in each opening **41b**. The wire engagement member **42** is constructed integrally with the globe supporting plate **41**, by cutting away the component material of the globe supporting plate **41** around the wire engagement member.

FIG. 4 shows a vertical section through the wire engagement member **42**. The wire engagement member **42** is comprised of a first portion **42a** that extends in an outward direction from the center of the globe supporting plate **41**, a second portion **42b** extending downwards from the first portion **42a**, a third portion **42c** that extends obliquely upwards from the second portion **42b**, and a fourth portion **42d** extending substantially horizontally from the third portion **42c**; the second portion **42b** and the third portion **42c** constitute a protruding portion **43** directed downwards.

In addition, the globe supporting plate **41** as well as the wire engagement member **42** is made of a metal with resiliency, and the tip **42e** of the fourth portion **42d** of the wire engagement member **42** can rotate vertically about the end **42f** of the first portion **42a**, that is, in the direction shown by the arrow **B**. Therefore, by pushing the tip **42e** of the wire engagement member **42** up or down, the protruding portion **43** rotates up or down.

As shown in FIG. 3, a hollow cylindrical globe **44** is mounted on the globe supporting plate **41**. The globe **44** is supported on the globe supporting plate **41** as it engages with the inside of the vertical lip **41a** created at the periphery of the globe supporting plate **41**. The globe **44** is made of thin, transparent glass, and is open at both the upper and lower ends.

The globe **44** is fastened to the globe supporting plate **41** by the ventilator **45** and the wires **46**. The ventilator **45** is composed of a cap-shaped component whose bottom is open, and two wires **46** are provided on the ventilator **45**, opposite each other, and are permitted to rotate freely in the direction of the arrow **C**. Each wire **46** is substantially rectangular in shape, and its length is almost the same as or slightly greater than the height of the globe **44**. More explicitly, the wires are shaped so that when the ventilator **45** is positioned at substantially the same height as that of the top of the globe **44**, the lower portion **46a** of the wire **46** can reach the bottom surface of the globe supporting plate **41**. Mounting and removing the globe **44** are performed for the gas lantern **30** according to the embodiment of the present invention, as follows.

When the globe **44** is to be installed, first the globe **44** is engaged with the inside of the vertical lip **41a** of the globe supporting plate **41**, thereby the globe **44** is located on the globe supporting plate **41**. Next, the ventilator **45** is placed on top of the globe **44**, and the two wires **46** are rotated towards the bottom surface of the globe supporting plate **41** so that the two wires pass around the outside of the globe **44**.

When the wires **46** have reached the bottom surface of the globe supporting plate **41**, the wires **46** move along the fourth portion **42d** and the third portion **42c** of the wire engagement member **42**. The protruding portion **43** comprising the second and third portions **42b**, **42c** of the wire engagement member **42** are thus pushed upwards by the wires **46**, so by moving the wires **46** along the fourth and third portions **42d**, **42c**, the protruding portions **43** gradually rotate upwardly. Eventually as shown in FIG. 4, the lower portions **46a** of the wires **46** moving in the direction of the arrow **S1** override the protruding portions **43**, and reach the first portions **42a** of the wire engagement members **42** where the wires stop. During this operation, to reduce the time for the lower portions **46a** of the wires **46** to override the

protruding portions **43**, it is preferable to push the protruding portions **43** up with the fingertips.

As described above, by engaging the two wires **46** respectively with the corresponding wire engagement members **42**, the globe **44** is fixed on the globe supporting plate **41**. FIG. 2 shows the state where the globe **44** has been fixed on the globe supporting plate **41** in the manner described above.

When the globe **44** is to be removed from the globe supporting plate **41**, the protruding portion **43** of the wire engagement member **42** is pushed up with a fingertip, and the lower portion **46a** of the wire **46** is made to override the protruding portion **43** in the direction of the arrow **S2**. As a result, the engagement of the wire **46** by the wire engagement member **42** is released, therefore the ventilator **45** and the globe **44** become free from the globe supporting plate **41**.

In this embodiment, four wire engagement members **42** are provided on the globe supporting plate **41**. However, it is not necessary to provide four members at all times. Instead, a minimum of two wire engagement members **42** can be incorporated opposite each other. When two wire engagement members **42** are provided, the wires **46** can only be engaged when they are aligned in one direction, but if four wire engagement members **42** are used, the wires **46** can be engaged when aligned in either of two directions.

Although the first means for wire engagement used in the aforementioned first embodiment of the present invention is comprised of a resilient metal, the first means for wire engagement can take another form, as follows.

FIG. 5 shows the first means used in the second embodiment of a gas lantern according to the present invention. FIG. 5 is a view of the bottom of the globe supporting plate **41** when the globe supporting plate **41** is viewed from below.

In the second embodiment, hemispherical convex bodies **47** are provided on the bottom surface of the globe supporting plate **41**, in place of the wire engagement members **42**. The convex bodies **47** are arranged in pairs, so a total of four pairs of convex bodies **47** are provided near the outer periphery of the globe supporting plate **41**; pairs of convex bodies are arranged diametrically opposite another pair such that their axes of symmetry are orthogonal.

Also with this embodiment, the globe **44** is fixed on the globe supporting plate **41** when the end portions **46a** of the wires **46** override the convex bodies **47** in the direction of the arrow **S1** and stop in the place shown in FIG. 5. For the reverse operation, when the end portions **46a** of the wires **46** override the convex bodies **47** in the direction of the arrow **S2**, engagement between the wires **46** and the convex bodies **47** is released, so that the globe **44** and the ventilator **45** become free from the globe supporting plate **41**.

However, the shape of the projections **47** is not limited to a hemisphere, and the projections may have other shapes. The projections **47** are not limited to a pair. In other arrangements, the projections **47** can be formed individually or combined into groups each of which is comprised of three or more projections **47**. In addition, it is not always necessary to provide four pairs of the projections **47**, and a minimum of two opposite pairs of the projections **47** is sufficient.

FIG. 6 illustrates the first means for wire engagement used in the third embodiment of the present invention for a gas lantern. FIG. 6 shows a bottom view of the globe supporting plate **41** when the plate is viewed from below.

This embodiment incorporates the first means for wire engagement including two grooves **48** each of which has a semi-circular cross section, formed on the bottom surface of

the globe supporting plate 41, instead of the wire engagement members 42. The grooves 48 are parallel to each other and a predetermined distance apart.

Also in this embodiment, the globe 44 is fixed on the globe supporting plate 41 when the end portions 46a of the wires 46 engage with the grooves 48 in the direction of the arrow S1. When the end portions 46a of the wires 46 are disengaged from the grooves 48 in the direction of the arrow S2, on the other hand, engagement between the wires 46 and the grooves 48 is released, so that the globe 44 and the ventilator 45 become free from the globe supporting plate 41.

FIG. 7 indicates the first means for wire engagement used in the fourth embodiment of the present invention for a gas lantern. FIG. 7 shows a view of the bottom of the globe supporting plate 41 when the globe supporting plate 41 is viewed from below.

In this embodiment, the first means for wire engagement is comprised of one wire engagement member 42 used in the above-mentioned first embodiment, and a cylindrical wire fixing tube 49 fixed on the bottom surface of the globe supporting plate 41. One of the two wires 46 is installed in the wire fixing tube 49 attached to the globe supporting plate 41 in a freely rotatable manner. That is, one of the wire 46 is fixed to the globe supporting plate 41, and cannot be removed from the plate.

In this embodiment, because one of the wire 46 is fixed to the globe supporting plate 41, the globe 44 can be mounted on or removed from the globe supporting plate 41, by engaging the other wire 46 with or releasing its engagement with the wire engagement member 42, respectively.

Using this embodiment, engagement between the wires 46 and the first means for wire engagement can be released by disengaging only one set of the wire 46 and its related means of engagement, so the globe 44 can be removed efficiently from the globe supporting plate 41. Because the ventilator 45 is permanently attached to the globe supporting plate 41 in the embodiment, the ventilator 45 can be prevented from being misplaced after being removed from the globe supporting plate 41.

FIG. 8 shows the first means for wire engagement used in the fifth embodiment of the present invention in a gas lantern. FIG. 8 is a view of the bottom of the globe supporting plate 41 viewed from below.

The embodiment is an example of using projections 47 as the first means for wire engagement, instead of the wire engagement member 42 shown in FIG. 7. Although not illustrated, it is possible to form the grooves 48 shown in FIG. 6, in place of the projections 47 shown in FIG. 8 as the first means for wire engagement.

While the present invention has been described in connection with certain preferred embodiments, it is to be understood that the subject matter encompassed by way of

the present invention is not to be limited to those specific embodiments. On the contrary, it is intended for the subject matter of the invention to include all alternatives, modifications and equivalents as can be included within the spirit and scope of the following claims.

The entire disclosure of Japanese Patent Application No. 9-266587 filed on Sep. 30, 1997 including specification, claims, drawings and summary is incorporated herein by reference in its entirety.

What is claimed is:

1. A globe supporting structure that supports a globe of a gas lantern which burns combustible gas discharged from a gas cartridge containing said combustible gas by means of a burner head located inside said globe, comprising:

a ventilator positioned above said globe;

a plurality of wires rotatably arranged on said ventilator, each of which rotates about said ventilator, and is shaped so as to be capable of reaching a bottom surface of said globe; and

a globe supporting plate that supports said globe, and is provided with first means which is detachably engagable with a portion of said wires reaching said bottom surface of said globe.

2. The globe supporting structure as set forth in claim 1, wherein said first means is provided with a protruding portion that protrudes downward, and can rotate in a vertical direction.

3. The globe supporting structure as set forth in claim 2, wherein said first means is made of a resilient material.

4. The globe supporting structure as set forth in claim 2, wherein said first means comprises a portion of said globe supporting plate, said portion being formed by cutting away a peripheral part of said globe supporting plate.

5. The globe supporting structure as set forth in claim 3, wherein the first means comprises a portion of the globe supporting plate, the portion being formed by cutting away a peripheral part of the globe supporting plate.

6. The globe supporting structure as set forth in claim 1, wherein the first means comprises at least one projection formed on a lower surface of the globe supporting plate.

7. The globe supporting structure as set forth in claim 1, wherein the first means comprises a recess that is formed on the lower surface of the globe supporting plate, and to which the wires are engaged.

8. The globe supporting structure as set forth in claims 1, wherein a plurality of wires are paired, and a wire of each pair is rotatably supported on the lower surface of the globe supporting plate.

9. The globe supporting structure as set forth in claim 1, wherein two of the wires are installed facing the ventilator, and two of the first means are formed on the globe supporting plate so as to be associated with the two of the wires.
